(57) **CLAIM**

We claim the ornamental design for a reticle for a gunsight or other aimed optical device, as shown and described.

DESCRIPTION

FIG. 1 is a view of a reticle for a gunsight or other aimed optical device, as viewed through an eyepiece end of a rifle-scope or other aimed optical device; and,

FIG. 2 is a perspective view showing of an environment of use for the reticle of FIG. 1.

In FIGS. 1 and 2, the dashed lines indicate environmental features that form no part of the claimed invention.
